UNITED STATES PATENT OFFICE.

CHARLES J. GREENSTREET, OF CHICAGO, ILLINOIS, ASSIGNOR TO GASOLINE CORPORATION, OF CHICAGO, ILLINOIS, A CORPORATION OF DELAWARE.

APPARATUS FOR CONTROLLING THE SUPPLY OF STEAM AND OIL TO AN OIL CRACKING STILL.

Application filed December 27, 1919. Serial No. 347,811.

This invention relates to an apparatus for adjusting the supply of steam to a still so that a proper flow is always insured.

It also relates to an apparatus for feeding oil and steam into an oil cracking still and is particularly applicable for use with the oil cracking still shown in the co-pending application of Charles J. Greenstreet, Serial No. 333,624, filed October 27, 1919.

10 The still described in that application is particularly useful with the Greenstreet cracking process set forth in Greenstreet Patent No. 1,110,924, September 15, 1914. In the practice of that process, steam and 15 oil are passed into a long coil where they are subjected to heat and pressure to crack the oils to change them from heavy hydrocarbons to lighter hydrocarbons. The process and apparatus permit the cracking process 20 to be carried on continuously without clogging which is one of the chief difficulties in most other forms of cracking stills.

A suitable fluid such as steam is used in the Greenstreet process for preventing the 25 formation of carbon deposits and the clogging of the apparatus. It is important, therefore, that the steam supply to the still always be adequate for the conditions under which the still is being run. Considerable 30 difficulty has been experienced in achieving this result with the usual valves and methods of determining the amount of steam flowing into the still. There is always a certain amount of play in a valve and the operator 35 is not always sure when he opens it a certain amount that the valve opening is correct and that a proper flow of steam is being secured. If the flow is not enough, the results are detrimental and the same is true 40 if the flow is excessive.

The present invention is directed, among other things, to a satisfactory practical solution of this problem.

One of the objects of the invention is to 45 provide an apparatus by means of which an operator can positively determine that the proper amount of steam is flowing into a still.

Another object is to provide an apparatus 50 for feeding oil and steam into a still which will insure that the proper flow of steam is being maintained.

Other objects and advantages of the invention will hereinafter appear.

An embodiment of an apparatus suitable 55 for the invention herein disclosed is shown in the accompanying drawing which is a side view of the still and the feeding apparatus therefor.

The still is described in detail in the application herein before referred to and is partially shown in a general way herein as a long continuous coil 1 of relatively small diameter through which commingled oil and steam are passed while subjected to heat 60 and pressure for cracking. Commingled oil and steam are passed to the coil through the entrance pipe 2, flow through the coil 1 where the oil is cracked and are passed out through pipe 3.

70 The steam is introduced into entrance pipe 2 through the pipe 4 and the oil through the pipe 5.

Located in the steam pipe is a supply valve 6 controlling the entrance of steam 75 into the pipe 4 from any suitable source of steam such as a boiler. A still valve 7 is also located in the pipe 4 for controlling the entrance of steam into the still. The steam pressure is determined by means of a gage 8 80 located as shown. Between the supply valve and the still valve there is located a steam outlet controlled by a valve 9 which when opened, permits the steam in pipe 4 to vent to the atmosphere.

85 By means of this arrangement the operator can positively and visibly determine when the proper amount of steam is flowing. He first makes sure that the still valve 7 is closed then opens the vent valve 9 and 90 finally adjusts the supply valve 6 until the stream of steam passing out to the atmosphere through valve 9 is of sufficient volume for the still requirements. He then closes the valve 9 and opens the still valve 7 permitting the stream of steam to flow to the still. 95 This permits the steam to be admitted to the still without requiring the further adjustment of the supply valve 6 and the operator knows that the proper volume of steam 100 is flowing.

The oil supply entering the pipe 5 is controlled by a valve 10 and its pressure is measured by a gage 11.

If too much oil enters the still without an 105 adequate supply of steam, the efficiency of the still is decreased and clogging may result. In order to guard against this, the

pressure of the steam is always maintained higher than that of the oil so that the steam will force its way into the oil and commingle with it in proper proportions whereas if the pressure were only equal to or possibly varied within limits close to the oil pressure there would be times when the steam pressure would not be sufficient to force the steam into the oil stream with corresponding detrimental results.

It will thus be observed that a practical simple apparatus has been devised for solving a problem that has given considerable difficulty in practice. The still operator can always positively determine that he has a proper volume of steam flowing and he can feel sure that the steam is commingling properly with the oil by reason of the fact that the steam is under greater pressure than the oil.

It is to be understood that the construction shown is for purposes of illustration and that variations may be made without departing from the spirit and scope of the appended claims.

What I claim is:

1. An apparatus for treating heavy hydrocarbon oils which comprises a heating coil, means for heating said coil, an intake pipe

leading to said coil and having two intake branches, one of said branches being adapted to be connected to a source of steam pressure and having therein a shut-off valve, a regulating valve for controlling the admission of steam, and a valve controlled vent to the atmosphere located between said shut-off valve and said regulating valve, and the other of said intake branches being connected to a supply of oil and having a shut-off valve therein.

2. An apparatus for treating hydrocarbon oils comprising a heating coil, means for heating said coil, an intake pipe for said coil having two branches, one connected to a source of steam and the other to a supply of oil, a cut-off valve and a regulating valve located in the branch connected to the steam supply, a valve controlled vent to the atmosphere located in said branch between said cut-off and regulating valves, and a pressure gage located in said branch beyond the cut-off valve, said oil supply branch being provided with a cut-off valve and a pressure gage.

In testimony whereof, I affix my signature.

CHARLES J. GREENSTREET.
